UNITED STATES PATENT OFFICE.

EDWARD H. ELLIS, OF PASADENA, CALIFORNIA.

DESIGN FOR A PIN-HOLDER.

SPECIFICATION forming part of Design No. 23,962, dated January 29, 1895.

Application filed December 13, 1894. Serial No. 531,735. Term of patent 3½ years.

To all whom it may concern:

Be it known that I, EDWARD H. ELLIS, a citizen of the United States, residing at Pasadena, in the county of Los Angeles and State of California, have invented and produced a new and original Design for a Pin-Holder, of which the following is a specification, reference being had to the accompanying drawings, in which—

10 Figure 1 is a perspective view of a pin-holder embodying my design; and Fig. 2 is a vertical, central section of the same.

The design is embodied in a saucer-shaped

pin-tray, *a*, a cup-like cushion-holder, *b*, fixed in the center of the tray, and a convex cushion, *c*, which is fixed in the holder, the said parts *a*, *b*, *c*, forming an ornamental attractive device. An ornamental band, *d*, surrounds the cushion adjacent to the edge of the holder *b*.

What I claim is—

The design for a pin-holder as shown.

EDWARD H. ELLIS.
